WOODEN SLAB FOR BUILDING PURPOSES

Uno Ivan Samuel Edlund, Akers Styckebruk,
SwedenApplication January 6, 1947, Serial No. 720,377
In Sweden September 21, 1943

2 Claims. (Cl. 20—91)

1

The present invention relates to the manufacture of reinforced wooden elements, or slabs, of flat shape especially for use in setting up moulds for concrete constructions.

Said elements according to the invention are built of pieces of board with their longer edges abutting against each other, said pieces of board being connected together, in part, by means of corrugated fasteners arranged so as to cross the joints substantially under right angles and, in part, by means of metallic bars engaging grooves formed in the ends of the connected boards which are sealed in this engagement by means of appropriate cramp-irons or the like. Said corrugated fasteners permit expansion of the boards owing to moisture and effect contractions thereof when the boards again become dry. The rods or bars engaging the grooves at the ends of the boards tend to maintain the boards of an element in the same plane, so as to prevent the element as a whole from warping while at same time armouring and stiffening it.

In the accompanying drawing an embodiment of the invention is shown by way of example.

Fig. 1 is a plan view of a slab constructed in accordance with this invention. Fig. 2 is a side view as seen in the direction of line II—II of Fig. 1. Fig. 3 is an end view. Figs. 4 and 5 are detail views on a larger scale showing a corrugated fastener as seen from its edge and in plan view, respectively.

A wooden element, or slab, according to this invention is built up of a number of pieces of board 1, with their longer edges abutting against each other or engaging each other by means of tongues and grooves.

To hold the pieces of board together corrugated fasteners 2 are utilized, which are driven into the pieces of board so as to cross the joints therebetween, substantially at right angles. Such fasteners may be used either on one surface of the slab only or on both surfaces thereof. In the said last-mentioned case it is preferred to displace the fasteners on one surface in the direction of the joints with relation to those on the other surface, as will appear from Fig. 2. In Figs. 4 and 5 a separate fastener is illustrated.

The fastening elements due to their corrugated shape allow expansions of the slab under the influence of moisture and act to draw the pieces of boards together when dried so as to avoid gaps between the individual pieces of board.

To hold the slab flat under all conditions and guide them under the said expansions and con-

2

tractions rods or bars 3 are used, let into grooves formed at the ends of the slab, each groove receiving a rod or bar that extends substantially over the entire width of the slab. To seal the rods or bars in the grooves cramp-irons 4 are used, which are driven into the pieces of board. At one end each rod or bar is sharpened to a point and bent so as to form a nail 5 that may be driven into the wood of the respective board. The rods or bars 3 act to maintain the boards of an element, or slab, in flat state, thereby stiffening it and keeping it from warping.

What I claim is:

1. A wooden element for use in setting up moulds for concrete constructions, comprising in combination, a set of pieces of boards placed with their longer edges abutting each other, so as to form a plane slab, said slab having grooves in opposite ends thereof the grooves at the respective ends being in alignment with each other, corrugated elastic metal fasteners driven into adjacent pieces of boards across the joints therebetween for keeping each two pieces of boards together while allowing expansion thereof under the influence of moisture and for positively drawing them close to each other when they become dry and contract, each such fastener to this end being of a length considerably shorter than the width of a piece of board, and metallic bars in said grooves, means for securing said bars against dislodgment from the grooves, said bars providing a flat state of the slab under variable conditions.
2. An element as claimed in claim 1, and in which one end of each metallic bar is formed with a bent pointed end for acting as a nail in engagement with the material of the slab.

UNO IVAN SAMUEL EDLUND.
